[57] CLAIM

The ornamental design for a dental floss holder, as shown and described.

DESCRIPTION

FIG. 1 is a perspective view of a dental floss holder showing my design;
FIG. 2 is a rear elevation view thereof;
FIG. 3 is a left side elevation thereof;
FIG. 4 is a top plan view thereof; the bottom plan view is the mirror image of the top plan view;
FIG. 5 is a right side elevation thereof; and
FIG. 6 is a front elevation view thereof.
FIG. 7 is a perspective view of a second embodiment of design;
FIG. 8 is a rear elevation view thereof;
FIG. 9 is a left side elevation thereof;
FIG. 10 is a top plan view thereof; the bottom plan view is the mirror image of the top plan view;
FIG. 11 is a right side elevation thereof; and
FIG. 12 is a front elevation view thereof.
